CUTTING CHAIN STRUCTURE

Charles J. Forbes, Terre Haute, Ind.

Application April 21, 1949, Serial No. 88,882

2 Claims. (Cl. 74—254)

1 This invention relates to a cutting chain structure comprised of connecting links alternated with and pivotally connected to adjacent straddle type links, each of the latter mounting a hooded holder, a bit, a complementary bearing member and a clamp screw.

One chief object of the present invention is to simplify the bit holding portion of the straddle link.

Another chief object of the present invention is to simplify the pivotal connection between said link and its associated connecting link.

One feature of the present invention resides in the broaching of the abutment portion of the straddle link to provide two overlapping parallel bores in one of which is seated the bit holder and in the other of which is seated a bit conforming hardened bearing member; the latter, when desired, being spot secured by welding in said receiving bore.

Another feature of the present invention resides in providing in the plate portions of the straddle link, pivot receiving bores, which bores detachably receive pivot forming tubular barrel members having non-rotative association with the said link and mounting a countersunk headed retainer that has a free end disposed angularly of the body portion, which free end is seated in registering notches in both barrel and link.

Other objects and features of the invention will be set forth more fully hereinafter.

The full nature of the invention will be understood from the accompanying drawings and the following description and claims:

In the drawings Fig. 1 is a side elevation of a portion of a cutting chain, parts being broken and shown in longitudinal central section to show same and other parts in greater detail.

Fig. 2 is a top plan view of the chain portion illustrated in Fig. 1.

Fig. 3 is a perspective view of the hooded bit holder.

Fig. 4 is a front elevation of the bearing member.

Fig. 5 is a perspective view of a diamond shape rhomboid type bit.

Fig. 6 is a sectional view taken on line 6—6 of Fig. 1 and in the direction of the arrows.

In Figs. 1 and 2 of the drawings, A indicates adjacent connecting links which are reduced at B between the ends, said ends being apertured at C and bushed at D with hardened sleeves having a length, see Fig. 6, substantially that of the width of the connecting links.

The straddle link comprises side plates 10

spaced apart slightly greater than the thickness of the connecting links so that said plates can accommodate and nest the adjacent ends of adjacent connecting links.

Each side plate 10, see Fig. 6, is correspondingly apertured at 11. On one side plate these apertures are circular. In the other they are shouldered as at 12. A tubular barrel pin 13 with bore 14 therethrough is shouldered at 15 in opposed relation. Bore 14 is countersunk at 16. Each side plate adjacent aperture 11, includes a longitudinally directed recess 17 in its outer face. These recesses or grooves are longitudinally aligned, see Fig. 2.

Preferably for strength retention they are not connected but they may be if desired. A pin 18 with head 19 to nest in countersink 16, see Fig. 6, is longer than the barrel and is disposed in the bore 14 thereof and its free end 20 is turned angularly to lie in cross-slot 21 of the barrel pivot and terminate in registering recess or groove 17 as shown in Fig. 1.

As shown in Figs. 2 and 6, no part of the pin or barrel pivot projects beyond the outside faces of plates 10. Also the barrel is rigid with the said plates by reason of shoulders 15 and 12, respectively, inter-engaging as shown in Figs. 1 and 6. Accordingly links A pivot upon fixed barrel pivots 13. Connection and disconnection can thus be readily effected.

The two plates 10 have inwardly directed upper lugs 22, see Fig. 2, and outwardly directed lower flange portions 23, see Fig. 1. Each plate thereabove includes a central slot 24 therethrough. One or both plates immediately therebeneath may include inwardly directed lug 25 which in emergency may serve as a stop.

The two plates 10 are suitably connected together by the upwardly extending fore and aft directed body portion 26, the front face 27 of which may be sloped slightly rearwardly. Extending downwardly and rearwardly therefrom is the threaded hole 28 to take dog clamp screw 29 having bearing end 30.

Extending downwardly from the top of the body portion are two circular outlined bores 31 and 32, see Fig. 1. These two overlap, as it were, see Fig. 2, and thus have communication for so much of their lengths as are in common. Bore 31 extends completely through the body. Bore 32 preferably does not.

Disposed in bore 32 is the hardened bearing member 33, see Figs. 1, 2 and 4. It has a flattened or reduced rear face 34 and a grooved portion 35 complementary to the associated portion of a

cutting bit 36 that bears thereon. Herein such bit 36 is illustrated as of diamond rhomboid shape, and includes two cutting tips 37 diagonally disposed upon the major diagonal.

Disposed in bore 31 is the shank 38 of the bit holder. Above the shank and rigid therewith is the fore and aft directed hood portion 39. The fore portion 40 is peak-like and includes connected forwardly directed edge portions 41 herein disposed in V-position to nest the adjacent position of bit 36 as shown in Fig. 1.

The rear face 42 is continued downwardly and rearwardly into the shank as at 43 and this portion is defined by the forwardly directed flange portions 44. These are carried forwardly and merge with each other. This forms the lower rear seat portion for the trailing end of the bit.

Note that herein the shank is solid at its inner end 45. It may, if desired, be hollow and the upper end of such bore would open upon the rear seat portion for powder discharge. Note also herein the lower end of the shank is substantial by cylindrical in outline so that rocking of the holder is prevented.

The trailing end of the hood prevents the holder dropping through the bore 31. Should breakage occur stop 25 prevents shank dropping into the chain driving sprocket.

Immediately above the lower end 45 of the shank and coincident with the lower end of the bit seating socket therein there is provided an inclined bearing portion 46. This is engaged by end 30 of dog screw 29 when the bit and holder is to be clamped in the body portion for cutting.

While the bearing member and holder are illustrated as disposing the bit in a plane coincident with the central longitudinal plane of the straddle link and the chain, it is to be understood the bit may be disposed at different angles to that plane as well understood in the art. In such cases bores 31 and 32 may be correspondingly inclined. Thus a single straddle link forging may be multiple broached at the desired angle to form bores 31 and 32. Hence but one forging die is required for all straddle links.

While the invention has been illustrated and described herein in great detail, same is by way

of example only and discloses the preferred embodiment of the invention, reference being had to the appended claims.

The invention claimed is:

1. In a cutting chain having alternated connecting and straddle links, the latter comprising spaced apart plate portions, the combination of a cylindrical barrel pivot at each end of the straddle link bridging the space between plates and extending through the adjacent end of a connecting link and pivotally supporting same, said pivot having a reduced square shoulder at one end, the straddle link having a complementary shoulder to prevent relative rotation between the straddle link and the pivot, the barrel pivot having a bore therethrough which is enlarged at one end, and a radial slot in the other end communicating with the bore and extending to the barrel periphery, and a pin seated in the bore and having at one end a head nested in the bore enlargement, the other end of the pin extending transversely of and disposed in the radial slot, one of the link plates having spaced apart wall divided recesses in its face at its opposite ends registering with the respective transverse pin slots and receiving the transversely disposed ends of the respective pins, said shoulders with said pin transverse end locking said barrel and links together.
2. Structure as defined by claim 1 wherein the slot is diametral in character, and the recesses in the plate are directed generally towards each other but have their adjacent ends spaced apart.
